PLAYER-PIANO ACTION.

1,022,066.

Specification of Letters Patent.

Patented Apr. 2, 1912.

Application filed April 12, 1911. Serial No. 620,588.

To all whom it may concern:

Be it known that I, SILAS S. DONOVAN, a citizen of the United States, residing at Meriden, New Haven county, State of Connecticut, have invented certain new and useful Improvements in Player-Piano Actions, of which the following is a full, clear, and exact description.

My invention relates to improvements in player piano actions which are arranged to be operated either by the usual keys of a keyboard or by mechanically actuated strikers.

The object of the invention is to provide means to prevent undue lost motion in the action as a result of the settlement of the key-bed or padding down of the felts after long continued use, this feature of the invention being of particular value in an instrument in which there is combined therein mechanically actuated strikers.

I will show my invention as applied to a well-known type of player piano action, therefore, as to such parts as constitute part of the known art, it will be unnecessary for me to describe at length the particular construction and details thereof.

In the accompanying drawings, Figure 1 is a side elevation of a combined manually and mechanically controllable action of a piano, in this instance of the upright type, although, of course, the same principle can be readily adapted to one of the horizontal type. Fig. 2 is a relatively enlarged detail view of certain parts. Fig. 3 is a perspective view of a detail.

1 represents a string; 2 a hammer; 3 a damper; 4 a jack; 5 a back-check; 6 a back-stop coöperating with said check; 7 a wippen; 8 an abstract; 9 a manually operable key; 10 an adjusting device between the key 9 and the lower end of the abstract 8, said adjusting device being customarily a capstan screw.

11 is a pad underlying and supporting the inner end of the key 9; 12 is a lug on the abstract 8 which carries an adjustable regulating button 14.

13 is a striker mechanically actuated in any desired way as by a crank 16 which in turn may be operated by an action pneumatic 17 (Fig. 2).

18 is a felt pad between the striker and the regulating button 14.

19 is a padded hammer rail.

As to the parts thus far described, the same are well-known details of a player piano action and hence, as to such details, it is unnecessary to describe the same further, it being sufficient to say that whenever the outer end of the key 9 is depressed manually, it will cause the hammer 2 to properly advance and strike the string, the damper 3 being simultaneously lifted from the string; and whenever the pneumatic 17 is collapsed, it will cause a similar movement of said hammer.

In actions of this type, it has been found that in time the key-bed sometimes settles and the supporting felt, particularly the felt 11, is padded down. This sagging or padding down of this particular felt disturbs the regulation of the action and it is for this reason that an adjustable capstan screw 10 is provided to correct said regulation. When the action is properly regulated, the operation of every hammer and damper is uniform and every hammer will be properly caught by the back-check 5 to prevent the improper action of the hammer which sometimes is so far improper as to cause, among other things, the hammer to give a distinct double blow to the string. In the proper regulation of a combined manually and mechanically actuated piano action, when the capstan screw 10 is properly adjusted, the very slightest pressure at the outer end of the key 9 will start the hammer. In other words, at this point there should be absolutely no lost motion. With the mechanical action, however, there is a distinctly different adjustment. Instead of having the striker 13 touch the regulating button 14 of the abstract under normal conditions, there is a slight clearance provided between said parts for the express purpose of providing a little lost motion at this point, thereby allowing for any tendency of the felt 18 to swell, and also guaranteeing a proper repetition which can only be reliably effected when the back-check 5 coacts properly with the hammer 2 through the stop 6. This fact is well understood by mechanics skilled in the art. From the foregoing it will be seen that in order to get the best results it is of great importance to maintain this clearance between the mechanical striker and the abstract. It will now be apparent that if the key-bed settles or if the felt 11 is padded down it would, unless guarded against, permit the abstract

to settle to a point where the proper clearance between the aforesaid parts would not be afforded, which clearance, if varied, impairs the regulation to a corresponding extent, and to a similar extent renders the action of the hammer imperfect. To guarantee a uniformity of the spacing between the mechanical striker 15 and the abstract 8, when the instrument is to be played mechanically, I provide an auxiliary support which may be moved into place and which, when in place, restores each element of the piano action to its original regulation even though the key-bed has sagged or the felts have been padded. This support may be constructed in a variety of ways, but I have shown herein a simple and effective device, comprising a swinging shelf 20, which, in this instance, is pivoted at 21 upon any suitable support. This shelf 20 extends under as many individual key actions as desired or as practicable in the particular piano to which it is applied, and its function is to raise the outer end of the wippen 7 to the desired, or originally regulated, position from which it may have settled for any of the reasons aforesaid. In this particular instance the wippen 7 carries an adjusting button 22 which is engaged by the regulation restoring shelf 20. Upon referring to Fig. 2, the shelf is shown in solid lines in the position it will assume when lifting the wippen 7 to the proper regulated position for mechanical playing. In the same figure the shelf is shown in dotted lines withdrawn from that position, as when the instrument is to be played manually, for at such times, of course, there should be no lost motion between the wippen and the inner end of the key 9. This supporting shelf 20 may be operated in any well known manner, but a preferred method of operation would involve a connection between said shelf and such part of the instrument as is operated as an incident preparatory to operating the instrument mechanically. For example, in many pianos the front of the case is provided with a so-called hinged key-slip 23, which is utilized as one of a variety of means for sealing expression devices (not shown) when the instrument is not being employed for mechanical operation. When such a hinged key-slip is employed as shown in the drawings, Fig. 2, there may be arranged between said key-slip and said supporting shelf suitable connecting mechanism whereby the mere act of turning down the key-slip will move the shelf 20 from the position shown in dotted lines to that shown in solid lines. In the drawings I have shown one preferred means, which comprises a slide 24 having a cam or incline 25 which supports a slide bar 26, the upper end of which engages with the shelf 20 or an extension 27 thereon, so as to lift the latter and

swing the shelf in the manner described. The two positions of the slide 24 and the associated parts are indicated in solid and dotted lines respectively in Fig. 2. When the upright slide bar 26 descends, the shelf 20 will likewise swing down by gravity, or said movement may be assisted by a spring 28. It should be understood, of course, that there are various intervening constructions in action mechanism between the hammer proper and the key and the striker, and that in a broad sense this invention should not be regarded as being limited to the particular system of intervening construction herein illustrated since the same widely vary. I have found that when the instrument has been once regulated properly with the lost motion taken up between the key and the hammer and the proper lost motion afforded between the hammer and the striker that it is seldom necessary to correct the regulation to adjust more than the capstan screw, since in most all cases the lost regulation, so-called, occurs from one or the other of the two causes originally mentioned, namely, the sagging of the key-bed or the padding down of the felt which supports the inner end of the key. The other pieces of felt commonly employed in action mechanism are all so comparatively thin and carry such comparatively small weight that padding down at such points is comparatively insignificant; however, in this as in most piano actions, I may provide the usual adjusting devices as shown at the various padded points for taking up any variation in the thickness of the padding at any one or more of such points.

What I claim is:

1. In a player piano action, a hammer, manually controllable means for operating said hammer, mechanically controllable regulated means for operating said hammer, intervening parts between said hammer and each of said operating means for transmitting movement of either to said hammer, adjustable regulating means for the manually controllable hammer operating means, and independent means for restoring the regulation between the hammer and the mechanical operating means therefor, in the event of settlement of said manually controllable hammer operating means, and means for moving said regulation restoring means into operation when the instrument is to be played mechanically, and for moving said regulation restoring means out of operation when the instrument is to be played manually.
2. In a player piano action, a hammer, manually controllable means for operating said hammer, mechanically controllable regulated means for operating said hammer, intervening parts between said hammer and each of said operating means for transmitting movement of either to said hammer, adjustable regulating means for the manually controllable hammer operating means, and independent means for restoring the regulation between the hammer and the mechanical operating means therefor, in the event of settlement of said manually controllable hammer operating means, and means for moving said regulation restoring means into operation when the instrument is to be played mechanically, and for moving said regulation restoring means out of operation when the instrument is to be played manually.

ting movement of either to said hammer, 5
adjustable regulating means for the man-
ually controllable hammer operating means,
means independent of the hammer and
striker for restoring the regulation between
the hammer and the mechanical operating
means therefor in the event of settlement of
the manually controllable hammer operating
means.

10 3. In a player piano action, a hammer,
means for operating the same including a
manually operable key and a mechanically
operable striker, intervening parts between
the hammer and both of said operating de-
15 vices, said parts including a wippen, adjust-
able means for regulating the position of the
striker relatively to said wippen, other adjust-
able regulating means for said key, and a
manually controllable means for taking up
20 lost regulation between said wippen and
striker when the instrument is to be played
mechanically and in the event of settlement
of the key adjustment.

25 4. In a player piano action, a plurality of
hammers, a plurality of manually operable
keys for operating said hammers, a plurality
of mechanically operable strikers for oper-
ating the hammers independently of the
30 keys, intervening parts between all of said
hammers and all of said operating devices
for transmitting the movement of the latter
to said hammers, a device for regulating the
operative position of each of the keys rela-
tively to its respective hammer, another de-

vice for regulating the operative position of 35
each of the strikers relatively to its respec-
tive hammer, and a manually operable take-
up device arranged to co-act with the parts
between a plurality of the hammers and
their respective strikers to reestablish the 40
regulation between said hammers and
strikers in the event of lost regulation be-
tween said parts due to settlement of the key
regulation.

45 5. In a player piano action, a hammer,
manually controllable means for operating
said hammer, mechanically controllable reg-
ulated means for operating said hammer, in-
tervening parts between said hammer and
each of said operating means for transmit- 50
ting the movement of either to said hammer,
adjustable regulating means for the man-
ually controllable hammer operating means,
independent means for restoring the regu-
lation between the hammer and the mechani- 55
cal operating means therefor in the event of
settlement of the key regulation and means
for moving said regulation restoring means
into operative position when the instrument
is to be played mechanically, and for mov- 60
ing said regulation restoring means out of
operative position when the instrument is
to be played manually, said means comprising
a hinged key slip.
